UNITED STATES PATENT OFFICE

FERDINAND H. BORM, OF CHICAGO, ILLINOIS

RAZOR STROPPING MACHINE

Application filed December 10, 1926. Serial No. 153,740.

This invention relates to improvements in the art of abrading mechanism, and more particularly to apparatus for sharpening edge tools and especially razor blades.

5 The primary object is the effective sharpening of such tools without injury thereto and regardless of variations and irregularities such as usually exist incident to slight deflections or other out-of-alignment conditions 10 of such edges.

A more detailed object is the rectifying of the location and condition of the serrations or "teeth" making up a cutting edge without danger of breaking such serrations, or tearing, distorting, or otherwise injuring the material of the blade along the line of such serrations.

20 A still more detailed object is the provision of a burnishing or abrading surface sustained by a hard and stable sub-support which still possesses a capacity of flexing sufficiently freely to enable the edge of a razor blade or other edged tool to find contact with the abrading surface without either excessive 25 flexing of the edge or depression thereof into the engaged surface.

With these and other objects in view, as will in part hereinafter be stated and in part become apparent, the invention comprises a 30 burnishing or abrading surface and a flexible support therefor constructed to allow the surface to give prior to any injurious deflecting of the blade edge but not to flex in a manner to produce or endanger embedding of the 35 edge in the burnishing or abrading surface.

The invention further comprises a hard, rigid support capable of maintaining its normal contour under usual stresses but sufficiently flexible to give under a stress some- 40 what less than that necessary to injuriously flex a portion of the edge of a blade.

The invention also comprises certain other novel constructions, combinations, and arrangements of parts as will be hereinafter specified and subsequently pointed out in the appended claim.

In the accompanying drawings

50 Fig. 1 is a plan view of a stropping machine embodying the features of the present invention.

Fig. 2 is a transverse section therethrough taken on the plane indicated by line 2—2 of Fig. 1, parts being seen in elevation.

Fig. 2a is a fragmentary section of parts as seen in Fig. 2 but illustrating an exaggerated distortion of the blade and its effect on the drum.

Fig. 3 is a view in side elevation of one of the abrader drums detached.

Fig. 4 is an end elevation thereof looking from the right hand end as seen in Fig. 3.

Fig. 5 is a perspective view of the inner clamping plate and stabilizer detached.

Fig. 6 is a similar view of the supporting shell of one of the abraders detached.

Fig. 7 is a similar view of the outer clamping plate.

Fig. 8 is a transverse section through a modified form of abrader.

Fig. 9 is a side elevation of the shell portion of the structure seen in Fig. 8, detached, intermediate portion being broken away for the saving of space.

Fig. 10 is a detailed fragmentary section of parts seen in Fig. 9, the parts being shown on an exaggerated scale.

It should be understood by those familiar with the art to which the present invention pertains, that edges of edged tools however fine and perfect appears under a microscope as a line of irregular saw teeth or serrations, and, in the forming of especially fine edges such as required for razor blades and the like, particular care is exercised to utilize material for the edge and to so treat it in the

sharpening process as to avoid as far as possible any cracking or opening of the material rearward of the valleys between the teeth.

Any such cracking largely destroys the support for the teeth and therefore permits the teeth to more readily bend or otherwise flex

permanently out of alignment. It is understood of course that whether the material of the edge is flawed rearward of the teeth valleys or not, any substantial permanent deflection of the teeth from alignment, results

in a dulled edge, and cracks or flaws, though microscopic, thus increase the ease with which an edge may be dulled. Excessive or repeated deflecting of the teeth in an effort to bring

them into alignment or otherwise sharpen them frequently results in crystallization along the line of flexing, and the teeth break off and leave a nicked edge. It frequently occurs in the formation of edged tools, especially razor blades, that the degree of precision in the approximation of the edge to a straight line is not very high. Some blades are flexed toward one end portion, others toward another, and still others more or less bowed or otherwise out of perfect line. Such irregularities are usually not great enough to be readily perceived by the naked eye but when the blade is laid against an abrading or polishing surface, a certain amount of stress must be exerted on one relative to the other to cause all parts of the edge to simultaneously contact with the surface. If the alignment is sufficiently accurate to enable such contact with sufficiently limited stress on the teeth of the edge little if any harm will be done, but beyond a certain point of deflecting to reach contact with the abrading surface the strain would be sufficiently great to cause or tend to cause the forming of the object flaws or cracks extending inward from the valleys between the teeth with a resulting permanent injury to the blade. It is a primary object of the present invention to enable effective sharpening of blades without danger of any such injurious results, and for the purpose of convenience, the term "abrade" will be utilized hereinafter to signify any action destined to or intended for the restoration of a dulled blade to a sharpened condition, it being understood that the term "burnishing" herein employed is only distinguished in degree from abrading, and in many instances the sharpening is affected without actual abrading or removal of material from the edge of the blade, the sharpening action in such case comprising merely the restoration of the teeth of the edge to a cleaned and aligned condition. Therefore, in the appended claims, the terminology should be interpreted to include this form of sharpening even though the term "abrade" be utilized to describe the actions.

Referring to the drawings by the numerals, 1 indicates a frame or housing in which are journaled the abraders designated generally by the reference numeral 2, and each comprising a drum provided with a terminal pinion 3 meshing with the pinion of the other drum 2 and so located as to effect successive buffing, burnishing or abrading action on the blade to be sharpened. Any appropriate actuator, such as crank 4, is connected to the extended shaft 5 of one of the drums 2 so that the drums may be revolved manually. Pendant lips 6—6 formed integral with or approximately fixed to the housing of frame 1, near the opposite ends thereof, form supports and guides for the blade 7 for retaining it rigidly in place during the sharpening operation.

The blade 7, as illustrated, is of the wafer type provided with a single cutting edge and a stiffening back at the opposite edge, but of course it should be understood that any type of blade may be effectively treated by an embodiment of the present invention, suitable supporting and shifting apparatus being employed as is well known in this particular industrial art. The blade holder 6 and form of the frame 1 may be modified to any extent well within the intent and purpose of the present invention, and it should be further understood that, while the abrading drums are shown as of a peculiar contour hereinafter to be described in greater detail so that during revolution one abrading surface contacts with the edged portion to be acted upon while the other is out of contact therewith and the latter is brought into contact after the former has left contact and so on alternately, the invention is well adapted for apparatus in which the abrading action occurs otherwise than as stated.

Referring more particularly to the buffing, burnishing, or abrading drums 2, each being a duplicate of the other, one only will be described in detail. A sub-support or backing tubular plate or shell 8, preferably of metal, is arranged to form a substantially solid, hard support for the abrading material 9 which is usually of leather but of course may be of any suitable and appropriate material and is provided in the form of a strip, wrapped about and snugly fitted on the exterior surface on the shell 8. The shell 8 is preferably formed of relatively thin sheet metal, such as brass, but may be made of any other material capable of the functions herein set forth for this element of the structure such, for example, as insulating fibre or material having a cellulose base. The shell 8 must afford a hard and substantial support for the abrading material 9, and yet be capable of flexing under that degree of pressure, a reasonable latitude of safety being provided, represented by the capacity of the edge of the blade 7 to flex without danger of crystallization or other injury, so as to enable the abrading surface 9 to stroke all parts of the edge of the blade despite irregularities in the alignment of such edge. In Fig. 2a there is illustrated an exaggerated distortion of the blade 7, seen at 7', which requires the flexing, at 8', of the shell 8. The exaggeration is necessary for purposes of clear illustration since the usual extent of flexing is ordinarily so slight as to be difficult of observation with the naked eye. The shell 8 is parti-cylindrical, that portion carrying the abrading material 9 which is to contact with the blade being transversely struck on the arc of a circle described from the axis of the drum 2 as its center. It will be apparent that the extent of the curved surface on said circle is capable of a wide range of

variation, and I prefer to utilize substantially all of the area or approximately all of the area on the curve of said circle which is capable of acting against the blade being sharpened while the other drum is out of contact therewith so that there will be a minimum of interim between the time one abrader leaves contact with one side of the blade and the other abrader reaches contact with the other side thereof. It will be readily understood that the fact that the shell 8 is made of material affording stabilized flexibility will be largely negated if the end portions of the shell 8 were rigidly held against flexing. Hence, in making up the abrading drum, those parts of the end portions of the drum which are liable to require flexing are not anchored to the heads of the drum hereinafter to be described, but are left free to flex throughout that portion corresponding with the parts of surface 9 positioned for and capable of engaging the edge of blade 7.

The shell 8 is made up of a curved sheet of material whose longitudinal edges are preferably spaced and provided with interned, anchoring tabs 10, and, when the shell is assembled as a part of the abrading drum, an inner supporting and clamping plate 11 is arranged within the shell, and an outer clamping plate 12 is disposed exteriorly of the shell along the line of the opening between the edges of the shell and overlapping parts of the body of the shell. The plate 11 is provided with slots 13 through which the tabs 10 are extended, and, in the completed drum, are clenched as clearly seen in Fig. 2. The plate 11 is provided with a flat base through which the slots 13 are formed, and, along the edges of the flat base, the plate is bent at each side to form inclined side sections or wings 14—14, each terminating in a flattened edged portion 15 disposed to rest against and support the shell 8. Wings 14 are therefore stabilizing braces tending to limit flexing of those portions of the shell 8 beyond the areas of the surface 9 capable of contact with the edge of the blade 7. The braces 14 also aid in preventing any tendency toward a permanent distortion of parts of the shell 8. The leather strip or other abrading material 9 is preferably stretched tightly upon or otherwise caused to snugly enclose and engage the shell 8, the terminal portions of the strip 9 lying between the exterior clamping plate 12 and the shell 8, as clearly seen in Fig. 2. The clamping plate 12 is susceptible of a wide range of variation, but, as seen in the drawings, consists of a substantially flat plate formed with inclined edged portions 16—16 terminating in serrated edges 17—17 set substantially at right angles to the sides of the body of the plate 12 so as to enter and effectively grip the strip 9 for preventing the possible slipping or loosening thereof. The body of the plate 12 is also provided with

stamped-up penetrating tabs or points 18—18 entering the material of strip 9 for further resisting movement thereof independently of the shell 8. The tabs 18 may be of any desired form, number, and arrangement but are preferably disposed, as clearly seen in Fig. 2, in such angular or inclined relation to the plate 12 as to best resist any withdrawing stresses on the strip 9 relative to the clamping plate 12. The clamping plates 11 and 12 are firmly and effectively secured together in any acceptable and appropriate manner. One method of such fastening consists in the employment of tubular rivets or eyelets 19 extending through apertures 24—24 in the plates 11 and 12. As many such eyelets may be employed as found desirable. I have illustrated the use of only two but a greater number under some conditions may be preferable.

Extending outwardly from and formed integral with the various parts of the plate 11 and its bracing wings 14 are anchoring tabs 20—20 which in the assembled drum serve as the connecting means to the heads of the drum. The drum is provided at each end with a head 21 of an edged contour conforming to the transverse contour of shell 8 after the clamping plates are in place, that is to say each head is parti-circular with a flattened part corresponding with the flattened part of the shell 8, which produces in effect an eccentric mounting of the drum. Each head 21 is formed with a series of slots 22, corresponding in number and location to the tabs 20, and proportioned to receive the said tabs. The tabs 20 extend through the respective slots 22 and are swaged or otherwise upset, as indicated at 20' in Fig. 4, at the outer face of the respective drum head 21 so as to provide a rigid anchorage of the plate 11 and all parts connected to it to the said drum heads. Extending outwardly from each drum head 21 is an appropriate trunnion or journal 23, the two being in axial alignment and being mounted in appropriate bearings at the ends of the case of frame 1. To one of the journals 23 is fixed the respective pinion 3 which meshes with the corresponding pinion of the other drum, and extended shaft 115 also outstands from said journal 23.

In operation, the crank 4 is revolved after the manner of the functioning of any of the well known types of razor sharpening machines, the blade 7 being in place. The abrading surfaces of the two drums are thus caused to successively engage the opposite sides of the edged portion of the blade 7 and to act upon the same as heretofore stated, the abrading surface 9 flexing with the shell 8, as at 8', when required, but maintaining its normal contour at all other times. No condition of any average blade 7 will be such as to cause the edged portion thereof to enter or imbed itself in the material of the surface 9 because

of the hard, resisting character of the sub-support provided in the shell 8.

In Figures 8 and 9 I have illustrated one modified embodiment relating more particularly to the construction of the supporting shell. In this embodiment the shell 8a is formed from a coiled spring and preferably each helix being flattened to provide a requisite eccentric exterior surface of the finished drum. The material employed to produce the coiled spring making up the shell 8a is preferably of flat spring material as seen best in Figure 10. Mounted on the shell 8a is the abrading material 9a and the said shell and the abrading material are clamped by the plates 11a and 12a and the parts are otherwise constructed after the manner above described with respect to the form and details of the abrading drum. Obviously, the shell 8 may be made up of numerous other forms than as seen at 8a while possessing the requisite capacities above indicated and all well within the scope and intent of this invention.

It will be apparent from the foregoing that the invention is characterized in that by the use of an effective embodiment thereof a blade may be sharpened without injury, and by injury is included weakening, or crystallization, or permanent deflecting of any portion of the edge.

What is claimed is:

A device of the class described comprising, in combination, a housing; a blade holder mounted within said housing; a drum member rotatably mounted within said housing; said drum member composed of a flexible cylindrical shell, said shell having a flattened portion; end members for said shell having openings thereon, stropping material disposed upon said shell; clamping means comprising opposed clamping members, one of said members engaging the inner portion of the shell and the other member engaging the stropping member; lugs on the ends of one of said clamping members adapted to engage the openings in said end members whereby the clamping members, and shell, are secured to said end members.

In testimony whereof I have signed my name to this specification.

FERDINAND H. BORM.
